CAGO, ILLINOIS, TRUSTEES.

CARBURETER.

1,373,550.

Specification of Letters Patent.

Patented Apr. 5, 1921.

Application filed May 12, 1917. Serial No. 168,325.

To all whom it may concern:

Be it known that I, MILFORD G. CHANDLER, a citizen of the United States, residing at Chicago, in the county of Cook and State of Illinois, have invented a certain new and useful Improvement in Carbureters, of which the following is a full, clear, concise, and exact description, reference being had to the accompanying drawings, forming a part of this specification.

My invention relates to carbureters and particularly to a carbureter arranged for lifting liquid fuel from a main source at a lower level to the level of the carbureter.

Fuel lifting carbureters are desirable because they make it possible to locate the main fuel tank in a convenient place at the rear of an automobile and they at the same time prevent waste of fuel by leakage at the carbureter float valve during non use of the automobile.

Carbureters have been proposed for this purpose which maintain a high vacuum in the mixing chamber and utilize this unenhanced vacuum suction for lifting the fuel to the float chamber of the carbureter. Such carbureters are somewhat unsatisfactory because the vacuum maintained in the mixing chamber, if sufficient under all conditions to lift the fuel, is such as to decrease the power of the engine because of the rarefaction of the explosive mixture entering the engine. This reduces the efficiency of the carbureter.

By my present invention I am able to maintain in the float chamber of the carbureter a greater reduction of pressure than that of the mixing chamber. I am at the same time able to maintain at the opening through which fuel is delivered from the float chamber into the mixing chamber a still greater depression than that of the float chamber, so that a sufficient pressure differential is continually maintained for delivering the proper proportion of fuel to the passing column of air.

One feature of my invention resides in the peculiarly shaped primary Venturi tube which is arranged to provide a sudden volumetric increase in size at the point where fuel is delivered to the Venturi tube, the object of this being to avoid a reduction of the degree of vacuum maintained at such point, which is, ordinarily incident to the admission of hydrocarbon fuel into a column of air passing through a Venturi tube.

Another feature of my invention is the particular form of regulating device which is so arranged as to maintain substantially constant the speed of the passage of air past the point in the primary Venturi tube at 60 which communication is taken off from the Venturi tube to the upper spaces of the float chamber. By means of this arrangement the fuel delivery is kept properly proportioned by a slight change in the degree of vacuum 65 applied to the fuel jets of the fuel nozzle.

Other features of my invention reside more particularly in the features of construction fully set forth in the following specification and claims.

My invention is illustrated in the accompanying drawings in which like characters represent like parts in the several views, and in which—

Figure 1 is a horizontal cross sectional view of the carbureter of my invention; and

Fig. 2 is a vertical cross sectional view taken along the line 2—2 of Fig. 1 looking in the direction indicated by the arrows.

Referring first to Fig. 1, the carbureter of 80 my invention comprises a casing 3 and a casing 4' secured to the former, as illustrated. The casing 3 has secured thereto or forming part thereof a float chamber 4 provided with the usual float and valve 85 mechanism for controlling the supply of fuel to the float chamber. As most clearly shown in Fig. 2, the lower end of the float chamber is provided with a coupling 5 arranged to communicate with a supply conduit 5' in turn extending downwardly into a fuel supply reservoir S located below the normal level of the fuel in the float chamber. The casing 3 carries the usual flange 6 adapted to be attached to the intake manifold of an internal combustion engine. Extending longitudinally through the casing 3 is a bore 7 containing a throttle valve 8 at a point posterior to the fuel nozzle, as will be described in detail hereinafter. The bore 7. 90 is enlarged at 9 where it communicates with the bore 10 provided in the casing 4'. The fuel nozzle is designated in its entirety at 11 and is disposed within the bore 7 of the casing 3. An auxiliary air valve is provided at 105 12 in the bore 10 of the casing 4' at a point anterior to the fuel nozzle. The fuel nozzle 11 is centrally disposed within the bore 7, as illustrated, and is supported by a vertically extending support 13 most clearly 110

shown in Fig. 2. The support 13 carries the internal threads 14 adapted to coöperate with the external threads of a primary Venturi tube 15. The Venturi tube 15 contains 5 the two annular grooves shown at 16 and 17 which coöperate with the support 13 so as to provide two annular chambers, as shown in Fig. 1. The Venturi tube 15 contains the primary air passageway 18 extending longitudinally therethrough. Affording communication between the passageway 18 and the chamber 16 at a point slightly anterior to the greatest constricted portion of the passageway 18 is an opening 19 which serves 10 to provide a vacuum or reduction of pressure in the chamber 16 when the internal combustion engine with which the carburetor is associated is operated. Extending through the support 13 and communicating 15 with the chamber 16 is a conduit 20 extending through the wall of the casing 3 and into the wall of the float chamber 4 where it communicates with the float chamber at a point above the normal level of fuel 20 therein.

Slightly to the right hand side of the opening 19 (Fig. 1) the passageway 18 enlarges abruptly, as shown at 20', and then gradually increases in size to the extreme 25 right hand end of the Venturi tube. Extending between the chamber 17 and the passageway 18 at the point 20' where the passageway suddenly enlarges I provide a plurality of fuel openings 21—21, the openings being preferably disposed at an angle tapering toward the head end of the Venturi tube. The chamber 17 communicates with a bore 22 extending vertically through the casing 3, as most clearly shown in Fig. 2. 30 The lower end of the bore 22 communicates with the horizontally disposed bore 23 in turn communicating with the lower end of a vertically disposed bore 24 in which an adjustable needle valve 25 is mounted. The 35 needle valve 25 is adapted to coöperate with the shoulder shown at 26 to regulate the passage of fuel through the bore 24. Communicating with the bore 24 at a point above the shoulder 26 is a bore 27 extending to the 40 float chamber 4 and at a relatively low point therein so as to feed the fuel from the float chamber to the bore 24 from which it is fed through the bores 23 and 22 into the chamber 17.

Carried by the casing 4' and having communication with the passageway 18 is a pipe 28 having its end 29 extending through the casing 4' and communicating with the atmosphere. The inner end of the pipe 28 carries 45 a spider 30 which serves to mount a regulating device 31 having an enlarged end or head 32 disposed in the passageway 18 and at a point adjacent the opening 19. The outer end of the regulating device 31 extends 50 through the pipe 28, as shown, and is

pivotaly attached at 32' to a link 33 in turn pivotaly connected at 34 with a lever arm 35. One end of the lever arm 35 is connected at 36 with a rod 37 reciprocably mounted in the casing 4' and connected to a piston 38 arranged to reciprocate within the chamber 39. A coiled compression spring 40 is interposed between the piston 38 and the casing 4' and tends normally to hold the parts in the position shown in the drawings. 55 The outer end of the chamber 39, or that portion disposed on the outside of the piston 38, has free communication with the atmosphere through the aperture 41 provided in the cap 42. The end of the lever 35 opposite the point 36 is pivotaly connected to the auxiliary air valve 12 at 43 so that upon inward movement of the piston 38 the auxiliary air valve 12 will be swung upon its pivot to permit the passage of air through 60 the bore 10 into and through the bore 7.

The bore 7 is provided with a secondary Venturi tube shown at 44 containing a constricted portion 45 located substantially opposite the head end of the Venturi tube 15. 65 Communicating with the atomizing chamber A and at a point slightly posterior to the constricted portion 45 is a conduit 47 terminating at and communicating with the inner end of the chamber 39 under the piston 38.

The operation of the device is as follows: Assuming the flange 6 to be attached to the intake manifold of an internal combustion engine, that the engine is operating at idling speed, and that the throttle valve 8 is opened, a vacuum or reduction of pressure will be produced in the mixing chamber A which results in the intake of air through the port 29, through the pipe 28, through the Venturi tube 15 into the mixing chamber from which it is taken into the engine cylinders. Since the head 32 of the regulating pin assumes a position where it restricts the passageway 18 to a considerable extent at 100 relatively slow engine speed, the air is caused to pass around the head 32 and in doing so attains great velocity which results in a vacuum or reduction of pressure 105 in the chamber 16, due to the fact that the chamber 16 communicates with the passageway 18 through the opening 19 at a point where the velocity of the incoming air is great. Since the chamber 16 communicates with the upper end of the float chamber 110 a high degree of vacuum or reduction of pressure will be provided above the level of the fuel in the chamber. As the speed of the engine increases the vacuum or reduction of pressure increases in the atomizing chamber A with the result that a vacuum or reduction of pressure will be provided in the chamber 39 below the piston 38 due to the conduit connection 47. Since 115 the outer side of the piston is subjected to 120 the pressure of the atmosphere the piston 38 is held in its normal position by the compression spring 40. As the engine speed increases the 125 vacuum or reduction of pressure in the atomizing chamber A increases to a point where the auxiliary air valve 12 is swung upon its pivot to permit the passage of air through the bore 10 into the bore 7. This air passes through the secondary Venturi tube 44 and the 130

atmospheric pressure the piston will be moved inwardly to open the auxiliary air valve 12 and thus permit the intake of air not only through the pipe 28, but also 5 through the bore 10. As the speed of the engine increases it is necessary to supply a greater amount of fuel to the incoming air. To accomplish this object the regulating device 31 is moved outwardly away from 10 the passageway 18 as the engine speed increases. As the piston 38 moves inwardly and the auxiliary air valve 12 swings about its pivot in a clockwise direction (Fig. 1) the lever 35 will be moved toward the 15 auxiliary air valve 12 and at the same time the end of the lever 35 attached to the auxiliary air valve will be moved away from the Venturi tube with the result that the regulating device 31 is withdrawn from the pass- 20 ageway 18. As the head 32 of the regulating device recedes from the passageway 18 it provides a greater area in the passageway through which the air taken in through the pipe 28 may pass and thus prevents increase 25 of velocity of the air at the point where the air passes the opening 19. As the volume of air taken into the carburetor increases, the regulating device moves outwardly, admitting a larger volume of air to the passageway 30 18, but as the movement of the regulating device makes the area of the passageway at the point 19 greater, the increase of volume of air passing through the passageway does not cause an increase in the 35 velocity of the air at the port 19. For this reason the vacuum at point 19, and consequently in the top of the float chamber is substantially constant. The area of the passageway 18 at the ports 20' does not change, 40 however, and as the volume of air passing through the passageway increases the velocity at ports 20' must also increase. Such action would therefore produce a greater degree of vacuum at higher speeds. Hence, 45 there would be a greater fuel feeding head at higher speeds and the flow of fuel would be greater at higher speeds than at low.

As the air passes the fuel openings 21 fuel is injected into the air and the intermixed 50 fuel and air delivered to the atomizing chamber A. The abrupt enlargement of the passageway 18 at the point 20 is provided so as to produce a sudden volumetric increase in size of the passageway 18 at the 55 point of delivery of fuel to the Venturi tube, it having been found by experiment that such an enlargement produces a greater local pressure reduction on the fuel ports than if the bore is only gradually enlarged 60 as is common practice. I have no satisfactory explanation for this action.

Having thus described my invention what I claim as new and desire to secure by Letters Patent of the United States is:

65 1. In a carburetor, a primary venturi, a

constant level float controlled fuel chamber, a low level source of fuel supply, a conduit directly connecting the low level source and the fuel chamber, a passage connecting the lower part of the fuel chamber and the 70 throat of said venturi, a second passage from a point near the throat of said venturi but anterior to the fuel delivery opening therein to the upper space of the fuel chamber for maintaining a vacuum in the upper part of 75 the fuel chamber, a movable regulating device for regulating the velocity of air past the said vacuum maintaining opening in said venturi for regulating the suction at said opening, and means for automatically mov- 80 ing said regulating device to different positions dependent upon the quantity of air drawn into the carburetor.

2. In a carburetor, the combination of a constant level float chamber, a fuel delivery 85 port slightly above the normal level of fuel in said float chamber, a main supply reservoir at a lower level, a primary Venturi tube, a conduit extending from the upper part of the float chamber to a point near the 90 throat of said Venturi tube for maintaining a partial vacuum in the float chamber, a conduit for delivering fuel from the float chamber to said delivery port, and a regulating device automatically moved into and out of 95 the opening in said Venturi tube to regulate the velocity of air past the point at which said vacuum producing conduit terminates in said venturi, and means for operating said regulating device proportionately to the 100 quantity of air taken into the carburetor, whereby the vacuum in the float chamber may be regulated and the proportion of fuel to air controlled.

3. A carburetor comprising an induction 105 passage, a fuel chamber, a fuel inlet in said induction passage, a conduit communicating with and extending between the induction passage and the upper spaces of the fuel chamber, means for changing the flow of air 110 through the induction passage at both the fuel inlet and the point of communication of said conduit with said induction passage, and further automatic means for maintaining the velocity of air past the point of communication of said conduit with the induction passage substantially constant.

4. A carburetor provided with an induction passage, a Venturi tube located therein, a fuel chamber, a fuel supply conduit ex- 120 tending between and communicating with the Venturi tube and the fuel chamber, a second conduit extending between the upper space of the fuel chamber and said Venturi tube and terminating in the latter at a point 125 near the throat thereof, and automatically operating means for regulating the velocity of air through said Venturi tube and past the point of communication between said last mentioned conduit and the Venturi tube, 130

said regulating device being adapted to differently regulate the velocity of air past the fuel delivery port in said Venturi tube, said regulating device being so shaped and operated as to provide a greater pressure differential between the openings of said conduits into said Venturi tube at higher engine demands than at lower engine demands.

5. A carbureter comprising a casing containing an atomizing chamber, a primary air intake passageway and a secondary air intake passageway communicating with the atomizing chamber, a Venturi tube forming a part of the primary air intake passageway, 10 a fuel chamber, a conduit affording communication between the Venturi and the fuel chamber at a relatively low level therein for feeding fuel to the Venturi tube, a second conduit affording communication between 15 the Venturi tube and the float chamber above the normal level of fuel therein, a regulating device disposed within the Venturi tube and arranged to restrict the passage of air therethrough, a throttle for the secondary 20 air intake passageway, a cylinder, a piston reciprocably mounted within the cylinder, a conduit extending between the cylinder and the atomizing chamber of the carbureter for producing a reduction of pressure within 25 the cylinder whereby the piston is moved in the cylinder, linkage extending between the throttle valve and piston and adapted to open the throttle upon operation of the piston, and devices connected with the piston 30 and operated thereby for withdrawing the regulating device from the Venturi tube upon operation of the piston in the direction to open the throttle.
6. A carbureter comprising a fuel chamber and mixing chamber, an air passage discharging into said mixing chamber, means for conveying fuel from said fuel chamber,

and discharging it into said air passage, a duct having one end communicating with the upper spaces of said fuel chamber and the other end discharging into said air passage, and means controlled by the pressure in the mixing chamber for varying the velocity of flow of air past the point at which the fuel is discharged into said passage without substantially changing the velocity of flow of air past the discharge end of said duct.

7. A carbureter comprising a fuel chamber and mixing chamber, an air passage discharging into said mixing chamber, means for conveying fuel from said fuel chamber, and discharging it into said air passage, a duct having one end communicating with the upper spaces of said fuel chamber and the other end discharging into said air passage, and means for varying the velocity of flow of air past the point at which the fuel is discharged into said passage without substantially changing the velocity of flow of air past the discharge end of said duct.

8. A carbureter comprising a fuel chamber and mixing chamber, an air passage communicating with said mixing chamber, a fuel duct leading from said fuel chamber and discharging into said air passage, a second duct leading from the upper spaces of said fuel chamber and discharging into said air passage, and automatic means for varying the velocity of flow of air past the discharge end of said fuel duct without materially changing the velocity of flow of air past the discharge end of said second duct.

In witness whereof, I hereunto subscribe my name this 10th day of May, A. D. 1917.

MILFORD G. CHANDLER.
